UNITED STATES PATENT OFFICE.

GEORGE A. SCHICK, JR., OF CAMDEN, NEW JERSEY, ASSIGNOR TO FERDINAND KELLER, JR., OF PHILADELPHIA, PENNSYLVANIA.

REINFORCED STRUCTURE AND METHOD OF MAKING SAME.

1,304,811.

Specification of Letters Patent. Patented May 27, 1919.

Application filed June 13, 1918. Serial No. 239,809.

To all whom it may concern:

Be it known that I, GEORGE A. SCHICK, Jr., a citizen of the United States, residing in Camden, New Jersey, have invented Reinforced Structures and Methods of Making Same, of which the following is a specification.

This invention relates to the art of reinforcing materials such as leather soles, belt-
10 ing or the like by closely placed lines of stitches made of relatively durable thread, and one of its objects is to provide such a structure in which the stitches shall not only be formed of a single length of thread in-
15 stead of two threads as has hitherto been the case, but shall also be of novel form.

Another object of the invention is to provide a new article of manufacture which shall include reinforcing transverse threads
20 so disposed as to provide on one face a series of projecting plugs whose arrangement shall be such as to materially increase the life and strength of the material to which they are applied.

25 Another object of the invention is to provide a novel method for inserting and forming a single thread in a body of sheet material so that it shall provide a series of stitches capable of serving as reinforcing
30 plugs for said material.

These objects and other advantageous ends I attain as hereinafter set forth, reference being had to the accompanying drawings, in which:

35 Figures 1 and 2 are respectively a plan and an inverted plan of a piece of flat material to which my invention has been applied;

Fig. 3 is a longitudinal vertical section on the line 3—3, Fig. 1; and

40 Figs. 4 and 5 are enlarged vertical sections taken at right angles to each other, illustrating my method.

In the above drawings, 1 represents a body of flat sheet material such as one or

45 more thickness of leather, canvas, fiber, composite sheet or the like which it is desired to reinforce. For this purpose it has formed in it a series of uniformly spaced, trans-
50 verse holes 2 made by an awl 3 operated by hand or forming part of a suitable machine. Thereafter, by means of a suitable needle, a thread, preferably of linen impregnated with a water proofing compound in a tem-
porarily semi-liquid condition, is drawn

through these holes successively, in each case 65 being formed in a loop x^1 . Said loop is then engaged by a second awl 4, the needle 5 is so moved as to disengage it from the loop and that end of the thread leading to the spool or other source of thread is pulled to di- 60 minish the size of the loop until this latter closely engages the awl 4 so as to draw it against the under side of the material 1 when said awl is withdrawn. The next 65 hole in the material is then formed by the awl 3, the needle 5 is passed through this hole so that its hook 6 engages the thread leading from the last formed plug or stitch and it is then operated to draw said thread through the hole to form a second loop. 70 As before the awl 4 is then projected be-
tween the sides of the loop, and is withdrawn after the thread has been drawn tight;—
the above cycle of operations being continued 75 indefinitely.

The plugs thus formed are obviously all made of a single length of thread and each has a looped head x^2 at one end of the hole in which it lies so that it projects beyond one face of the body of leather or other ma-
terial constituting the sheet or piece 1, there being on the opposite face of said body a series of straight thread sections x^3 all lying 80 in the same straight line. The size of the holes, the gage of the thread and the mate-
rial with which the latter is saturated, are such that when said material solidifies shortly after the formation of the plugs, 85 said holes are completely filled so that the passage of water, etc., is effectually pre-
vented. Moreover by the use of thread plugs each extending completely through the sheet in two parallel lengths in each hole, not only are the structural strength and wear 90 resisting qualities of the sheet materially in-
creased, but its tendency to break or crack 95 along the lines of stitches is effectually pre-
vented.

The projecting heads x^2 may serve, in the case of leather soles, as ground-engaging ele-
ments in which case they take an appreciable amount of wear from the body 1, and the stitching as a whole reinforces the strength 100 as well as prolongs the length of life of said structure. Moreover, by the use of my in-
vention the flexibility of the sheet material between successive stitches is increased and 105 by reason of the form and placing of said

stitches, there is no such cutting of the material by the thread from hole to hole as ordinarily occurs.

It is especially to be noted that with the 5 peculiar arrangement of the plugs and by reason of the method whereby they are formed, I am enabled to insert and retain the thread as desired and form the loops or stitches from but a single length of the 10 same, where hitherto it has been customary to employ two intermeshing or interlocked threads. As a consequence my invention permits of a material reduction in the quantity of thread required for a given reinforcement. 15

While the above thread reinforce and method of applying the same is particularly valuable for strengthening and increasing the wear-resisting qualities of the leather 20 of shoe soles, belting, etc., it may obviously be employed without departing from my invention for strengthening or reinforcing other forms of sheet materials.

I claim:

25 1. A new article of manufacture consisting of a body of sheet material, and a series of reinforcing plugs formed of a single length of thread, each consisting of two parallel portions extending completely through 30 the material and forming an independent, self retaining head on one face thereof.

2. A new article of manufacture consisting of a body of sheet material, with a single thread disposed in the form of a series of 35 loops extending through said material and formed into independent, self retaining heads adjacent one face thereof.

3. A new article of manufacture consist-

ing of a body of sheet material, and stitches therein consisting of a single length of 40 thread formed into a series of loops, each passing through the material in a single channel and terminating on one face thereof at one end of said channel in a closed looped portion constituting a head. 45

4. A new article of manufacture consisting of a body of sheet material and stitches therein consisting of a single length of 50 thread formed into a series of loops, each passing through the material in a single channel and terminating on one face thereof in a looped portion constituting a head, adjacent loops being connected on the opposite face of the body by straight portions extending in the same straight line. 55

5. The method of reinforcing sheet material which consists in forming a hole therein; drawing a loop of thread through said hole, then drawing back said thread against a retaining tension, to cause said loop to 60 form a head; and thereafter continuing to form a succession of holes and place headed loops therein.

6. The method of inserting a series of thread plugs in a body of sheet material 65 which consists in forming a hole in the material, placing a loop of thread therethrough, drawing back the projecting loop of said thread against a retaining tension to form a looped head on one face of the body 70 of material; and thereafter continuing to form holes and place headed thread loops therein.

In witness whereof I affix my signature.

GEORGE A. SCHICK, JR.
